UNITED STATES PATENT OFFICE.

THOMAS GARE, OF NEW BRIGHTON, ENGLAND.

ELASTIC TIRE.

SPECIFICATION forming part of Letters Patent No. 688,994, dated December 17, 1901.

Application filed September 9, 1901. Serial No. 74,800. (No model.)

To all whom it may concern:

Be it known that I, THOMAS GARE, a subject of the King of Great Britain, and a resident of New Brighton, in the county of Chester, England, (whose post-office address is Bramble Beach, Warren Drive, New Brighton,) have invented new and useful Improvements in and Connected with Elastic Tires, (for which I have made application for patent in Great Britain, No. 3,734, dated February 21, 1901; in France, dated June 20, 1901; in Belgium, dated June 20, 1901; in Germany, dated June 21, 1901; in Austria, dated June 19, 1901; in Hungary, dated June 19, 1901; in Italy, dated 15 August 21, 1901, and in Switzerland, dated August 21, 1901,) of which the following is a specification.

My invention relates to improvements on an invention for which Letters Patent No. 665,203, dated January 1, 1901, were granted to me, and has for its object to provide the tube or ring forming the wearing-surface of the tire described and shown in the specification belonging to the said patent with a wearing-surface which is readily renewable and greatly prolongs the life of the tire. I attain these objects by the mechanism illustrated in the accompanying drawings, in which—

Figures 1, 2, 3, and 4 are cross-sections of tires; and Fig. 5, a side view, partly in section, of a wheel complete at a reduced scale. Figs. 6 and 7 are two modifications of the removable wearing-surface.

Similar letters refer to similar parts throughout the several views.

In carrying out my invention and referring to the figures generally, *a* is the channelled rim; *b*, the rubber bed therein, having a groove *c*; *d*, the open tubular ring; *e*, the improved wearing-surface of the tire. Now instead of using the open tubular ring *d* as a wearing-surface I use an endless metal ring *e*, of suitable section, which I shrink onto the periphery of the said tubular ring. This outer ring *e* forms the actual wearing-surface, while the tubular ring *d* forms simply an intermediate body between the elastic bed *b* and the wearing-surface *e*, which intermediate body allows the wearing-surface *e* to be renewed. This 45 intermediate body, being rigid, prevents the wearing-surface *e* breaking through torture and allows the latter to be shrunk on without destroying or deteriorating the rubber bed *b*.

The rubber bed *b* thoroughly insulates the ring or wearing-surface *e* from the channelled 55 rim, and thus from the wheel and vehicle, which renders the wheel free from jars and vibration. The wearing-surface *e* also provides increased security of the intermediate body *d* in its elastic bed *b*.

Fig. 1 shows an oval and Figs. 2 and 3 a partly flat sectioned tubular ring *d*, the wearing-surface *e* being semicircular in Figs. 1 and 3 and in Fig. 2 nearly straight.

When using my improved tire to run on 65 rails, I form the ring or wearing-surface *e* with a flange *i* or on the channel-rim *a*, as shown in dotted lines, Fig. 2.

Instead of using an intermediate body *d* in a tubular form I may use a semicircular or 70 similarly-sectioned open metal ring *f* in the elastic bed or seat *b*, as shown in Fig. 4, to the outer periphery of which I then shrink the metal ring *e*, forming the actual wearing-surface.

The ends of the intermediate ring or body *d* I suitably connect together, say, by a tongue *g*, engaging in the ends thereof, and pins *h*, passed crosswise through the tongue *g* and ring or body, (see Fig. 5,) so as to prevent the 80 latter leaving the elastic bed or seat *b* should the ring or wearing-surface *e* have worn through at the joint of the intermediate ring or body *d* unnoticed.

To prevent the wheel skidding (slipping) 85 laterally or axially, the wearing-surface *e* may be formed with grooves, as shown in Figs. 6 and 7, which in some cases may be filled with leather or the like. (See Fig. 7.)

What I claim as my invention, and desire to 90 secure by Letters Patent, is—

In an elastic tire of the type hereinbefore specified, the combination of an outer endless ring *e* with an intermediate tubular open ring *d* crimped into the groove sides of a rubber 95 bed *c* in a channelled rim *a*, the said outer endless ring being shrunk onto the said intermediate tubular open ring and forming a renewable wearing-surface for the latter, all substantially as and for the purpose set forth. 100

In witness whereof I have hereunto set my hand in presence of two witnesses.

THOMAS GARE.
